HYDRAULIC VALVE LIFTING MECHANISM

Earl Lossau, Chicago, Ill.

Application January 29, 1940, Serial No. 316,151

11 Claims. (Cl. 123—90)

This invention relates to valve operating mechanism for internal combustion engines and the like.

The principal object of the invention is the provision of a new and improved mechanism for operating valves that are used in internal combustion engines and other places where the valve stems vary in length due to environmental heat.

Another object of the invention is the provision of a new and improved valve operating mechanism that is provided with means for automatically compensating for elongation and contraction of the valve stems during the operation of the engine.

A further object of the invention is the provision of a new and improved mechanism for engaging the plungers of the operating mechanism for opening the valves of the engine during its operation.

Another object of the invention is the provision of new and improved hydraulic mechanism for operating the valves of internal combustion engines together with novel means for replenishing the liquid in the mechanism and for maintaining substantially constant pressure on the liquid during the operation of the engine.

Other and further objects of the invention and advantages thereof will appear from the following description, taken in connection with the accompanying drawings, in which—

Fig. 1 is a front elevation of an internal combustion engine showing the invention in position thereon;

Fig. 2 is a vertical section of one of the valve actuating members;

Fig. 3 is a perspective view of a portion of the actuating mechanism;

Fig. 4 is a section on the line 4—4 of Fig. 1, with parts broken away;

Fig. 5 is a vertical section of the valve operating mechanism shown in Fig. 6; and

Fig. 6 is a transverse section thereof on the line 6—6 of Fig. 5.

Referring now to the drawings, the reference character 9 designates an internal combustion engine having a crank shaft 10. This engine may be of the conventional type, the one shown having four cylinders and comprising a conventional cylinder block 11, crank shaft 10; a crankcase 12, a casing 13, Figs. 1 and 5, for the magneto and driving mechanism therefor, and a cylinder head 14 in which are mounted the intake and discharge valves 15 and 16, respectively, for the engine. Each valve is provided with a spring 17 for seating the same in the usual manner. Since the details of the engine constitute no part of the invention, it is not thought necessary to further illustrate or describe the same.

It is common practice, in the construction of internal combustion engines, to provide tappets, in one form or another, for operating the valves from a cam shaft but since the valve stems become elongated by heat, it is necessary to provide clearance between the tappets and valve stems to compensate for the elongation. Increase of speed or an increase in the temperature of the surrounding air may cause the engine to run at higher temperatures and this in turn will cause additional expansion or elongation of the valve stems. At high speeds, if there is too much clearance between the valve and the tappet, considerable noise is developed and the timing is not accurate. If sufficient clearance is not provided, then the elongation of the stem will prevent the proper seating of the valves.

The present invention seeks to eliminate the necessity for the use of tappets by the provision of mechanism whereby a column of oil, under pressure, may be employed for operating the valves direct.

In the conventional internal combustion engine, a cam shaft is employed for operating the tappets, a cam for each tappet. The cam shaft extends along the engine so that the cams come opposite the valves. The friction between the cam and its tappet is such as to cause considerable wear on the tappet which in turn necessitates adjusting of the clearance between the tappet and the valve at comparatively frequent intervals, especially in engines used in aeroplanes, racing cars, and other high speed engines.

The present invention eliminates this difficulty by the provision of a minimum number of cams or eccentrics mounted on a short eccentric shaft or shaft having eccentrics thereon and provided with ball bearing contact members for reducing wear between the parts to a minimum.

The mechanism for operating the valves is an attachment that may be readily applied to the conventional engine of the valve-in-head type. This mechanism comprises what for convenience will be termed actuating mechanism 20, Fig. 5, and actuated means or mechanism 20a, Fig. 2. The former forces a liquid through a connecting conduit 48 for operating the latter and the latter in turn operates the corresponding valve, that is, the valve is opened when these mechanisms are operated.

The actuating mechanism is shown in Figs. 5 and 6 and comprises a casing 18 which is adapted to be secured to the cylinder block 11 in any suitable manner. This casing is in sections and comprises a unit 21 which carries cylinders 24 employed in controlling the operation of the intake valves and which, for convenience of description, will be termed the intake unit or intake valve control unit, and a unit 34 which car-

ries cylinders 24a employed in controlling the operation of the exhaust valves and will be termed the exhaust unit or exhaust control unit, Fig. 5. These units are alike except that they are rights and lefts.

The intake unit 21 comprises a pair of circular concentric bands or broad rings 22 and 23, Fig. 3, which are spaced apart to assist in forming an oil reservoir 35, as clearly shown in Figs. 5 and 6 of the drawings. These bands have attached thereto, or integral therewith, the cylinders 24 which have their inner ends attached to, or integral with, the inner band 23 and extend radially outwardly beyond the outer band 22. The bore of each cylinder extends through both bands or rings. There is a cylinder 24 for each intake valve of the engine, there being four in the present construction.

The cylinders 24 have, what will be termed, their forward walls or surfaces flush with the forward edges of the bands 22 and 23 and a front plate 25 engages the front edges of the bands 22 and 23, as shown in Fig. 5, to form an oil-tight joint. The plate 25 is provided with a rearwardly extending hub 26 which fits in the opening 27 within the inner ring 23 of the unit 21. The cylinders 24 each have, in the rear wall, adjacent the ring 22, an opening 28 for the passage of oil into and out of the cylinder, as will presently appear.

The exhaust control unit 34 is a complement of the intake unit 21 and is similar in construction thereto. The cylinders 24a of this unit are mounted on, or cast integral with, a pair of concentric bands 31, 32 in the same manner as the cylinders 24 of the previous construction. Since the construction of the cylinders 24a and bands 31, 32 are substantially the same, except rights and lefts, as the cylinders 24 and bands 22 and 23 of the unit 21, it is not thought necessary to repeat the description at this point further than to say that the cylinders 24a have openings 29 in their front walls opposite the openings 28 of the cylinders 24 for the intake and discharge of oil from the passage 33 into and out of the cylinders 24a.

The cylinders 24 of the intake unit are spaced forwardly from the rear edge of the bands 22 and 23 and the cylinders 24a of the exhaust unit are spaced rearwardly from the front edge of the bands 31 and 32 so that when the two units are placed together, as shown in Fig. 5, there will be an oil passage 33 between them, as shown in the lower portion of Fig. 5. There will also be a chamber 49 formed in the interior of the casing 50 extending axially thereof and surrounded by the rings 23, 31 and ring 42. The spaces between the cylinders 24 and those between the cylinders 24a, when the parts are assembled, will constitute a reservoir 35 between the inner and outer rings of the units, as shown in Figs. 5 and 6. The passage 33 will be in communication with the reservoir 35 so that the oil will be continuous between the inner and outer bands of the two units throughout their circumference. A plate 30 forms the rear wall of the reservoir 35 and engages the rear faces of the exhaust unit, as shown in Fig. 5. This plate 30 is provided with a hub 40 which extends into an axial opening in the intake unit. The units 21 and 34 and plates 25 and 30 are held in assembled relation by bolts 50 which clamp the parts together. These bolts extend through openings 60 in the end plates 30 and through the slots forming the oil reservoir 35 so that the units may be adjusted

circumferentially relative to each other in order that they may be set so as to cause the plungers 36 and 37 to operate in proper timed relation. Each cylinder of the intake unit is provided with a plunger 36 and each cylinder of the exhaust unit is also provided with a plunger 37, as shown in Fig. 5 of the drawings. Since the plungers and cylinders are substantially alike, only one need be described.

The plunger 37 of the cylinder 24, Fig. 5, will now be described. It has its inner end curved in cross-section, as shown at 38, in Fig. 5, and its outer end is hollow for receiving a spring 39 for normally urging the plunger 37 inwardly.

Suitable means are provided for limiting the inward movements of the plungers of both the intake and exhaust units. As shown, the inner adjacent edges of the inner bands 23 and 31 are rabbeted to form a groove 41 when the parts are assembled. An annular ring 42, having an annular projection 43 engaging in the rabbets, is provided for this purpose. The lateral edge portions of the ring are beveled off to form the inclined surfaces 44 and 45 on which the curved surface of the inner ends of the plungers 36 and 37 is adapted to seat for limiting their inward movement.

The outer ends of each of the cylinders of both units are provided with means for attaching communicating conduits thereto. Any suitable means may be employed for this purpose. In the form of the construction shown, the outer end of each cylinder is internally threaded and has attached thereto a threaded head 46 which is provided with an axial internally threaded tapered bore for receiving a threaded stud 47 through which extends a conduit 48 having its lower end expanded and secured in position by the stud 47.

Suitable means are provided for operating the plungers 36 and 37 in timed relation. In the form of construction selected to illustrate one embodiment of the invention, an eccentric or cam shaft 52 having what will be termed the intake eccentric or cam 54 and spaced angularly 180° therefrom an exhaust eccentric or cam 53 therein is employed for this purpose. The shaft 52 extends axially through the chamber 49 and is mounted in antifriction bearings 55 in a recess formed in the cap plate 26 and its rear end is enlarged and the enlargement mounted in antifriction bearings 56 mounted in an axial opening in the plate 30 and there are also antifriction bearings 57 mounted within a recess in a casing 58 which encloses a gear 59 that rotates the eccentric shaft to which it is keyed and which is rotated through suitable gearing 100 from the crankshaft 10 of the engine 9 at one-half the speed of said crankshaft. In order to reduce the wear and frictional resistance to a minimum, a suitable antifriction bearing, such as the ball bearing 61, is mounted on each of the eccentrics or cams 54 and 53. These ball bearings are held in position by retainer rings 62 at each side of the ball bearings which engage corresponding grooves in the eccentrics, as is usual in such constructions.

The actuated means or mechanism 20a for operating the intake and exhaust valves of the engine will now be described. Since the actuated mechanisms for the different valves are substantially alike, only one need be described.

Mounted on the cylinder head 14, above each of the valves, is a housing 63 having its inner end recessed or provided with an enlarged axial bore 64 and having a small bore 65 extending axially

from the enlarged bore 64 to the outer end of the housing. The bore 64 has mounted therein a spring 17, the inner end of which engages a bearing 66 for the stem 67 of the valve 15. The bearing extends through the cylinder head 14, as shown in Fig. 2. The outer end portion of the valve stem 67 is provided with an abutment member 68 rigidly attached thereto and against which the outer end of the spring 17 abuts. The valve stem 67 extends a short distance beyond the abutment member 68 for engaging a plunger 69 slidably mounted in the small bore 65. The outer end of the bore 65 is internally threaded for receiving the threaded end of a stud or cap screw 71 which is adapted to close the outer end of the bore. The inner end of the stud 71 is normally spaced from the outer end of the plunger 69 so as to form an oil space or chamber 72. The housing 63 is provided with a lateral opening 73 which is in communication with the chamber 72 and has attached therein the upper end of the conduit 48 by a suitable pipe fitting 74.

It will thus be seen that as oil is forced by the corresponding plunger 37 of the actuating mechanism into the tube 48, it will cause oil in the upper end of the tube 48 to flow into the chamber 72 under pressure thus forcing the piston 69 inwardly against the end of the valve 67 for opening the same, as will presently appear.

Suitable means are provided for maintaining oil under pressure within the reservoir 35 for supplying oil to the cylinders of the actuating mechanism. Any suitable mechanism may be employed for this purpose. In the form of the construction shown, a pump 75 is employed. The pump 75 may be of any suitable form, that shown being of the conventional gear type. The pump 75 has its intake in communication with the oil in the crankcase and its discharge in communication with a conduit 76, the upper end of which is secured in a housing 77 attached to the upper wall of the actuating mechanism, as shown in Fig. 6. The housing 77 comprises an upper section 78 and a lower section 79 which are adapted to be attached to the upper wall of the actuating mechanism 20 as by means of the cap bolts 81 which extend through both sections and are threaded into the wall of the casing for the actuating mechanism 20. The lower section 79 is provided with a bore 82 which is in alignment with an opening 83 through the casing of the actuating mechanism 20 and has, on its outer end, a valve seat 84 on which is seated a relief ball valve 85.

The upper section 78 is provided with a bore 86 for housing a spring 87 that has a bearing against the relief valve 85. The outer end of the upper section 78 is closed and means are provided in the outer end for regulating the compression of the spring 87. As shown, a stud 88 having a shoulder member 89 for forming an abutment for the outer end of the spring is provided for this purpose. A lock nut 91 locks the bolt in adjusted position. The housing is provided with an intake passage 92, inwardly of the relief valve 85, in which the upper end of the conduit 76 is secured. The housing is also provided with another opening 93 above the valve 85 in which is secured the upper end of an overflow pipe 94, the lower end of which is attached to the crankcase so that oil from the pump is forced through the conduit 76, bore 82 and opening 83 into the reservoir 35 for maintaining the oil therein under pressure and when the pressure exceeds a predetermined amount, the oil will escape through

the relief valve 85 and conduit 94 into the crankcase. In other words, the conduit 94 constitutes a bypass and the valve 85 a relief valve for the system.

In practice, the housing 77, with the relief valve 85, is placed at the upper portion of the actuating mechanism so that any air that may accumulate in the housing will be discharged through the relief valve 85.

In the operation of the engine, the oil pump is continuously operated so as to maintain a predetermined pressure on the oil in the reservoir 35 as has been already described. As the eccentric shaft 53 is rotated, the ball bearing on the eccentrics 53 and 54 will engage the plunger of the intake and exhaust units for forcing these plungers outwardly against the tension of the springs 39 and the springs will return the plungers to their seats on the inclined surfaces 44 and 45 after the shaft has turned the eccentrics so that the ball bearing does not engage the plungers. The ball bearings will strike the plungers at an angle to the radius of the bearings and this will cushion the blow as the outer ring of the ball bearing will turn when struck and roll across the plunger. The outer ring of the ball bearing will rotate in the opposite direction from that of the eccentric shaft.

Assuming that a plunger, such as 37 in Fig. 5, is at its lowermost position, the opening 29 in the forward wall of the cylinder 24a will be uncovered so that the oil under pressure from the reservoir 35 will completely fill the cylinder and also the conduit 48 and the space 65 above the plunger 69 of the actuated mechanism 20. Upon the engagement of the ball bearing of the eccentric 53, with the inner end of the plunger 37, the plunger will move upwardly forcing excess oil in the cylinder out through the opening 29 into the reservoir 35. After the piston moves outward a sufficient distance, it will close the opening 29 and then, on further movement, will force the liquid upwardly into the conduit 48 and since the liquid is substantially incompressible, this force will be transmitted through the conduit onto the oil in the chamber 65 and this in turn will force the plunger 69 inwardly against the compression of the spring 67 for opening the valves 15. When the eccentric moves to the position for releasing the plunger 37, the spring 39 will seat the piston 37 against the seat 45 and the spring 17 of the actuating mechanism 20 will seat the valve 15. As soon as the plunger 37 moves sufficiently to open the passage 29, the oil within the cylinder 24a will again be in communication with the oil reservoir and the pressure in the two will immediately equalize. The cylinder 24a is preferably of larger diameter than the cylinders 72 so that the plungers 37 will move only a fraction of the distance moved by the pistons 69. Any ratio may be employed but in the form of the construction shown, the ratio is 3 to 1; that is, the plunger 69 moves three times the distance of the plunger 37.

It will thus be seen that by means of this arrangement, the oil in the conduits 48 and actuated mechanism is continuously replenished each time the corresponding valve is operated because, after each operation, the pressure in the entire system is equalized. This is considered an important feature of the invention because it insures uniformity in the operation of the mechanism.

Assuming that the firing order of the engine is 1, 2, 4, 3 and that the shaft 52 is driven in the

same direction as the crank shaft 10 and the gear 59, then the operation of the intake valves will be represented in Fig. 6 by the corresponding numbers 1, 2, 4, 3 and the exhaust may be represented by 3a, 1a, 2a and 4a. In other words, when the exhaust for number 2 cylinder is actuated, the intake for valve number 1 would be operated simultaneously or with a slight lag.

The order of valve operation may be changed as desired since it would only necessitate changing the wiring for the spark and changing conduits 48 to the proper corresponding casings 63.

While in the present invention there are two cams or eccentrics, one for the exhaust valves and one for the intake valves, mounted in different planes, on the same shaft, it is understood that the cams or eccentrics may be mounted in the same plane on the shaft which may easily be done by arranging the cylinders 24 and 24a in a common plane spaced angularly instead of laterally.

It is thought from the foregoing, taken in connection with the accompanying drawings, that the construction and operation of my device will be apparent to those skilled in the art and that changes in size, shape, proportion and detail may be made without departing from the spirit and scope of the appended claims.

I claim as my invention:

1. In a valve operating mechanism for an internal combustion engine, an annular oil reservoir comprising a pair of concentric rings spaced apart, cylinders carried by said rings, the bores of said cylinders extending through both rings, a complementary set of rings spaced apart radially and having cylinders rigidly connected thereto, the bores of said cylinders extending radially through both of said last-named rings, and circular end plates secured to the outer sides of both sets of rings to form an annular chamber defined by said plates and rings.

2. In a device of the class described, a multi-cylinder internal combustion engine, an intake and an exhaust valve for each cylinder, an oil reservoir in the form of a hollow annulus secured to the said engine and arranged in a vertical plane, a short shaft having a pair of eccentric enlargements thereon extending axially through said hollow annulus, hydraulic mechanism for operating said valves, said mechanism comprising conduits for containing oil, one for each valve, an inner and an outer cylinder and plunger at the inner and outer ends of each of said conduits, respectively, the plungers at the inner ends of said conduits being arranged radially in a circle around said shaft, said inner cylinders having ports in the side walls in communication with said reservoir and adapted to be opened and closed by said inner pistons in timed relation, and a ball bearing secured on each eccentric enlargement and having its outer races engaging said inner plungers for operating the same for hydraulically operating the outer plungers for opening the corresponding valves.

3. In an internal combustion multi-cylinder engine having an engine casing surrounding the engine, intake and exhaust valves for said engine, a cam shaft casing secured to an end of said engine casing and comprising a central hollow portion, a comparatively short horizontally arranged shaft rotatably mounted in said hollow portion, eccentric cam elements on said shaft, all the cam elements being arranged in two vertical planes, a liquid reservoir formed by said shaft casing isolated from said hollow portion and

adapted to be filled by a liquid, a plurality of cylinders within said shaft casing and extending radially across said reservoir each having an opening in its side wall in communication with said reservoir, said second-named cylinders being arranged radially around a circuit, valve operating means, each means comprising a piston and a cylinder for each valve within said engine casing, a liquid filled conduit between each cylinder in said cam shaft casing and a corresponding cylinder of said means, the piston of each means being inwardly of the corresponding conduit and engaging a corresponding valve stem, a plunger in each cylinder in said cam shaft casing movable to a position to close said opening and beyond for operating the piston of the corresponding member, said last-named plungers each being adapted to be engaged by one of said cam elements for causing said last-named plungers to operate the pistons of the valve operating means by hydraulic pressure through said conduit, and means for maintaining a constant pressure on said reservoir during the operation of said engine.

4. In a valve operating mechanism for an internal combustion engine, a casing, a short shaft having eccentrics thereon within said casing, anti-friction bearings on said eccentrics, an annular oil-filled reservoir extending around said shaft and spaced therefrom, cylinders extending radially through said reservoir and having ports in the side walls thereof in communication with said reservoir, pistons within said cylinders engaging said anti-friction bearings, valve operating plungers, cylinders for said plungers, oil-filled conduits forming liquid columns between said pistons and plungers whereby when said shaft is rotated for reciprocating said pistons the reciprocation of said pistons will intermittently open and close said ports and will operate said plungers in response to the operation of said pistons while said ports are closed, and means for maintaining a substantially constant pressure of the oil within said reservoir.

5. In an internal combustion engine having a cylinder casing provided with a plurality of cylinders and intake and exhaust valves for each cylinder, a casing secured to the front end of said cylinder casing, said second-named casing being provided with radially arranged cylinders, pistons in said last-named cylinders, said second-named casing having a reservoir containing a liquid in communication with each of said last-named cylinders when the cooperating piston is at a predetermined position in its cycle of operation, a valve operating plunger, a cylinder for said plunger, a liquid column between each plunger and its corresponding piston, cam means for operating said pistons for operating said valves through said liquid columns and said plungers, said reservoir surrounding and spaced from said cam means, and means including a pump and a relief valve for supplying oil from the crank case of said engine to said reservoir and for maintaining the volume and pressure on said reservoir substantially constant while said pistons are inoperative during the operation of said engine.

6. In an internal combustion engine, a cylinder block comprising a cylinder head, a set of intake and a set of exhaust valves slidably mounted in said head, a short shaft, a pair of eccentrics carried by said shaft, a ball bearing for each eccentric, each ball bearing having its inner race rigidly mounted on the corresponding

eccentric, hydraulic means including a body of liquid and a liquid column for each valve for operating the latter, means for placing the liquid column intermittently in communication with said body of liquid, said means comprising cylinders arranged radially around said shaft, two sets of reciprocating plungers for said cylinders arranged radially about the outer races of said ball bearings and engageable therewith for operating said liquid columns, two sets of plungers engaged by the outer ends of said liquid columns for opening said intake and exhaust valves in timed relation to the operation of the first-named plungers, spring means for closing said valves, and means for automatically maintaining said body of liquid under a substantially constant pressure during the operation of said engine, and adjustable means for varying such pressure.

7. In an internal combustion engine having a plurality of cylinders, an intake and an exhaust valve for each cylinder and a crank case for containing lubricating oil, hydraulically operated mechanism for independently operating said valves, said mechanism comprising an annular receptacle containing oil, a cylinder for each valve extending radially into said receptacle and having a port in its side wall, a plunger for each cylinder, a piston in contact with each valve, a column of oil between said plunger and piston for each valve, means for operating said plungers for alternately opening and closing said ports and for reciprocating said oil columns for operating said valves, and means including a pump and a spring-pressed check valve opening in the direction of flow of oil through the last-named means for supplying oil from the crank case of said engine to said mechanism and for maintaining a constant pressure on the oil within said receptacle.

8. In an internal combustion engine having a plurality of cylinders, intake and exhaust valves for said cylinders, hydraulic mechanism for operating said valves, means for operating said mechanism, said mechanism comprising an annular reservoir for containing oil, two sets of cylinders extending radially into said reservoir, both sets being arranged around said reservoir in separate vertical planes adjacent to each other, each of said cylinders having a port in its side wall in communication with the oil in said reservoir, a piston for each of the last-named cylinders, an intake and an exhaust valve for each of the first-named cylinders, means including conduits and hydraulic columns of oil within said conduits for operating said valves by said pistons, respectively, means including a pump for automatically maintaining a constant super-atmospheric pressure on the oil in said reservoir during the operation of the said engine, a conduit between the crankcase of the engine and the upper portion of said reservoir, a supply conduit between the pump and said reservoir, means for controlling the amount of pressure on the reservoir, said means comprising a spring-pressed valve in said first-named conduit above the reservoir adapted to be opened when the pressure within said reservoir exceeds a predetermined amount, and means for operating said pistons in a predetermined order for causing the operation of said intake and exhaust valves.

9. In an internal combustion engine having intake and exhaust valves, an annular casing secured to the front end of said engine and hav-

ing a liquid reservoir therein, valve actuating plungers within said reservoir, means including a pair of eccentrics for operating said plungers by said engine, valve operating pistons, hydraulic means including conduits and a column of oil for each conduit engaging the corresponding valve for operating the same and for operating said pistons when said plungers are operated, cylinders extending through said casing for said plungers, said liquid reservoir being in communication with each cylinder at a predetermined position in the movement of said plungers, a liquid within said reservoir, means including pump mechanism for automatically maintaining a super-atmospheric pressure on said reservoir, a conduit in communication with the upper portion of said reservoir, a pressure operated valve within said conduit for conducting air and liquid from said reservoir when air accumulates therein and the pressure therein rises above a predetermined amount, and means for adjusting the pressure at which said valve will open.

10. In a valve operating mechanism for an internal combustion engine comprising actuating pistons, actuated plungers adapted to engage the valves of said engine, a plurality of liquid columns for transmitting force from said pistons to said plungers for operating said plungers, a liquid reservoir, means for placing the columns of liquid, first one and then the other, independently of one another, in communication with the liquid in said reservoir for replenishing loss of liquid in said columns, a housing extending upwardly from the upper portion of said reservoir and in communication therewith, a conduit connected to the base of said housing above said reservoir, means including a pump for continuously discharging a liquid into said housing through said conduit, an outlet in communication with said housing above said reservoir, and an adjustable pressure relief valve in said outlet above said reservoir for maintaining a constant pressure on the liquid within said reservoir and for permitting the discharge of air that may be pumped into said reservoir.

11. In a device of the class described, a multi-cylinder internal combustion engine, intake and exhaust valves for each cylinder, an oil reservoir casing formed by two hollow annular members engaging each other, side plates engaging the outer faces of said members and cooperating with said members to form said reservoir, one of said members having a set of cylinders extending radially through said reservoir for the intake valves of said engine and the other member having a second set of cylinders extending through said reservoir for the exhaust valves of said engine, a plunger for each cylinder, actuated mechanism comprising a piston and a cylinder for each valve mounted adjacent to each valve, a conduit between each cylinder of each set and the corresponding last-named cylinder, said conduit and reservoir containing oil, means for adjusting one of said members angularly relatively to the other, a short shaft, a pair of eccentrics on said shaft, a pair of ball bearings having their inner races fixed on said eccentrics, the outer race of ball bearings engaging said plungers for operating the corresponding pistons for operating the intake and exhaust valves of said engine, respectively, said reservoir extending around said eccentrics and spaced therefrom.

EARL LOSSAU.
